UNITED STATES PATENT OFFICE.

CLARENCE W. COLEMAN, OF WESTFIELD, NEW JERSEY, ASSIGNOR TO THE HALL SIGNAL COMPANY, A CORPORATION OF MAINE.

ELECTRIC SWITCH INSTRUMENT.

No. 927,714.

Specification of Letters Patent. Patented July 13, 1909.

Application filed December 22, 1905. Serial No. 292,982.

To all whom it may concern:

Be it known that I, CLARENCE W. COLEMAN, a citizen of the United States, and a resident of Westfield, in the county of Union and State of New Jersey, have invented certain new and useful Improvements in Electric Switch Instruments, of which the following is a specification.

This invention relates to the instruments 10 to be used in combination and in coöperation with track devices such as track switches, track indicators, signals, etc.

The instrument comprises electric switching devices which are designed to control 15 electric circuits.

In its usual embodiment the invention applies to such an instrument as may be exposed to the weather without injury to the switching devices. In its best form it is 20 adapted to be connected with the operating rod of the track device in any one of the various positions which may be most suitable for each instrument. To accomplish this latter result the various operating elements 25 of the instrument are made reversible and thus operative in two directions, the co-operating switching devices are likewise reversible and interchangeable.

Further objects of the invention are the 30 positive operation, both opening and closing, of the switching devices by a fractional movement of the track device, at least in one direction or the other, between normal position and slight displacement, and the 35 locking of the switching devices throughout the remainder of the movement of the track device. These functions may be best illustrated in connection with the operation of a track switch. When a track switch is being shifted the associated indicator or signal 40 should indicate the slightest displacement from normal position, and again when the switch is being replaced to normal the signal should not indicate normal until that position is actually reached, while until these 45 critical movements of the track device occur the original signal indication must be maintained.

An additional feature of the invention is 50 the construction of a device which is suffi-

cient in itself to meet the conditions required of more than one ordinary instrument.

The preferred embodiment of the invention and its application is illustrated more particularly in the accompanying drawings in which like reference numerals designate corresponding parts in the various figures, and in which:

Figure 1 is a sectional elevation of the 60 complete instrument, on line 1—1 of Fig. 2 looking in the direction of the arrows. Fig. 2 is a top plan view of the instrument with its cover removed. Fig. 3 is a detail elevation of the end of the rocker frame. Fig. 4 is a diagram illustrating the application of the instrument to a track switch. Fig. 5 is a diagram illustrating the electrical connections of the switching devices in association with an electrically controlled signal. Fig. 6 is a detail section through the line 6—6 of Fig. 2 looking in the direction of the arrows.

Referring now more particularly to the drawings:—1 is a case preferably of cast iron which serves as the support for the switching 75 devices and their operating mechanism.

2 is a cover for the case which may be locked thereon by means of a staple and hasp 66 and 67 and the pad-lock 68.

The case 1 is attached to some suitable 80 support 15 such as a tie or signal post by means of lag screws 3.

Journaled in the case 1 is a rock shaft 7 with a crank 5 fixed thereto outside of the case 1 and adapted to be connected with the 85 operating rod for the track device. Fixed to the rock shaft 7 within the case 1 is an actuating reciprocating member 10, 11 extending radially from shaft 7 and provided with a curved bearing surface at its upper 90 portion, which surface is provided with a projecting tooth 32, which is arranged to engage and actuate a notched device 24 which is secured to a rotary electric switch member or rocking frame 20, which together 95 with the electric contacts may be termed a rotary electric switch. This member 20 is rotatably or swingingly mounted at its ends on the shaft or axis 25 extending substantially at right angles to the path of move- 100

ment of the reciprocating member 10, 11. The member 10, 11 is moved commensurately with and proportionally to the movement of the track device by some direct connection. When the tooth 32 operatively engages the notched device 24 in the notch or face 26, the rocking frame or rotary electric switch member 20 is rotated clockwise or counter clockwise according as the movement of the tooth 32 is to the left or to the right, considering the apparatus to be as shown in Fig. 1. The rotation of the member 20 is limited in a counter clockwise direction by the flat engaging face or stop 33 and in a clockwise direction by the flat engaging face or stop 34 formed respectively on opposite sides of the notch 26 and adapted to engage the outer curved face of the reciprocating segment 11. Coöperating with the faces or stops 33 and 34 is an engaging means or locking lug 29 adapted to engage first the outer face and then the inner face of the segment 11. Thus, when the member 20 is rotated counter clockwise, as shown in Fig. 1, the reciprocating segment 11 locks member 20 against rotation by means of its engaging relation to the engaging face or stop 33 and the lug 29; the lug 29 prevents a clockwise rotation of member 20 and the face or stop 33 prevents any continuation of a counter clockwise rotation thus locking member 20 against any rotation. When the member 20 is rotated clockwise, the segment 11 again locks the member 20 against rotation by means of its engaging relation to the engaging face or stop 34 and the lug 29, the lug 29 having passed through a notch in the segment 11 so as to engage the inner face of the segment instead of the outer face of the segment as it did when the member 20 was rotated counter clockwise and as shown in Fig. 1. In this case, the lug 29 prevents a return counter clockwise rotation of member 20 and the face or stop 34 prevents a continued clockwise rotation of member 20 and therefore locks member 20 against any rotation.

The rotary electric switch member or rocking frame 20 is connected at its sides by insulated links 51, 52 with switching devices 48, 50. These switching devices are mounted upon an insulating base 17 carried by the shelf 16 formed on one wall of the case 1. These switching devices are connected in circuit with a signaling device or devices, such as an indicator or signal, in any suitable manner. One application of the same is illustrated in Fig. 5 while Fig. 4 illustrates the mechanical connection of a track switch with the switch instrument when the switching devices are connected as illustrated, in Fig. 5. From an examination of Fig. 1 it is evident that the tooth 32 operates positively upon the rocking frame to actuate the switching devices when it moves in either direction.

Specifically the crank 5 is fixed to the shaft 7 by means of the key 6 while the rocking segment 11, cast integrally with the web 10, legs 9, and hub 8 is fixed to the shaft 7 within the case 1 by means of the set screw 59 which permits the segment 11 to be adjusted in its proper position on the shaft 7, and to be removed, reversed and replaced on shaft 7 so that the tooth 32, locked in a notch near one end of the actuating member 10, 11 by a bolt 31, may be shifted symmetrically with reference to its operating position relative to the rotary electric switch member 20. The segment 11 is provided with two slots 12 and 13 to permit the lug 29 to pass through the segment. 13 is for the passage of the lug with the segment as shown in Fig. 1 and 12 is for the passage of the lug when the segment is reversed.

The rocking frame 20 comprises a spacing rib 23 of cast metal, half tubular in form, and two shafts 21 and 22 extending parallel thereto and supported by yokes 69 and 70 extending at right angles to each side from the ends of the rib 23. The rocking frame is journaled on a shaft 25 which is supported by uprights 63 and 64 integral with the case 1, and constituting the sides thereof. The cotter pins 59 and 62 serve to hold the shaft 25 in place. At one end of the rocking frame 20 is a notched device 24 which is cast integrally with the members 23, 69 and 70. The side of the notched device 24 adjacent to the segment 11 has two inclined faces 33 and 34 forming an obtuse angle, with a groove 26 at the intersection. The yoke 69 is provided with two slots 27 and 28 located on either end thereof and in vertical alignment with the shafts 21 and 22 respectively. These slots provide for the reception of an interchangeable lug 29. The lug 29 is formed integrally at its rear with a perforated supporting link 30, adjacent to which the lug 29 is recessed on its upper portion as indicated by a dotted line in Fig. 3. The lug 29 is illustrated projecting from the slot 28 with the perforated link 30 lying against the rear face of the member 69 while the shaft 22 passes through the upper end of the link 30. Thereby the lug 29 is held up in the slot 28, the sides of which prevent any lateral motion of the lug. See Figs. 3 and 6. If the instrument should be adjusted to operate in the reverse of what is illustrated, then the lug 29 would occupy the slot 27 and the link 30 would change places with the washer 57 on the shaft 21. As illustrated in Figs. 1, 2, 3 and 6, the member 30 embraces the shaft 22 while a spacing washer 57 of the same width as member 30 occupies a like position on the end of the shaft 21. Each of the shafts 21, 22 is provided with a series of interchangeable members which may be located thereon in various relative positions to operate according to the particu-

lar manner of connecting up the switching instrument with its associated devices. As illustrated in Fig. 6 each shaft is first inclosed by an insulating tube 72 which extends from the members 57 and 30 respectively to the opposite yoke 70.

55 designates insulating washers one on each end of the tubes 72.

52 designates the link sleeves integral with the connecting links 54. These link sleeves embrace the insulating tube 72.

58 designates blank sleeves of insulating material which correspond in size with the link sleeves 52 and which serve to fill the places left on the tube 72 designed to receive link sleeves in case the latter are re-arranged to suit an interchange in the position of the switching devices.

56 designates interchangeable insulating washers alternating with the link and blank sleeves.

The shaft 21, likewise surrounded by an insulating tube 72, supports link sleeves 51 exactly similar to and interchangeable with the link sleeves 52 on the companion shaft. It is also provided with sleeve blanks and insulating washers like those on shaft 22 but arranged in the inverse order.

All the similar parts borne by the two shafts 21 and 22 are reversible and interchangeable and need not be located precisely as illustrated in the drawings but should be so located that they may properly coöperate with the switching devices which the links 25 actuate according to the location of the switching devices.

16 is a shelf projecting from the interior wall of the case 1, over-lying the shaft 7 and supported by two brackets 14 which extend 40 out from the wall of the case, one on either side of the shaft 7.

Spaced from the shelf 16 by an insulating member 18 and attached thereto by screws 19 is an insulating base 17 to the upper face 45 of which are fixed the switching devices. The switching devices are all reversible and interchangeable. Two sets are illustrated in Figs. 1 and 2. The switching devices of the first set comprise a blade member 48 of spring metal 50 which is attached to the base 17 by means of an integral base member 44 and the screw 46. This base member is supplied with a binding post 38. The blade member and the base member are formed of a single piece of 55 spring metal bent as illustrated into a Z-shaped contour. The operating ends 47 of the blades are twisted at 90° to the base members 44 and blades proper to form knife contacts to which the links 54 are pivoted 60 respectively and which coöperate with the contacts 43 also secured to the base 17 by screws 45 and provided with binding posts 35.

48 designates the blades of the switching devices in one set, while 50 designates the 65 blades of a second set and, as is illustrated,

the position of the latter on the base 17 is the reverse of that in the first set. The blades 50 have operating ends 49, base members 40, actuating links 53, contacts 39 secured to the base by screws 41, and have binding posts 70 37, all corresponding to the similar parts described with reference to the blades 48.

The base portions 40 and 44 are attached to the insulating base 17 by means of the screws 42 and 46 and are provided with binding posts 36 and 38.

In the drawings four switching devices are illustrated, arranged in two sets of two devices each. The sets are oppositely arranged so that when one set is open the other is closed. The reversibility and interchangeability of these devices permit that they be grouped in any desired manner. They might all be similarly disposed and open together. Also if desired any number might be removed 85 and those remaining would still operate. Likewise by lengthening the frame 20 others might be applied and operated by additional links.

Although the switch contacts illustrated in 90 coöperation with the rocking frame or rotary switch member 20 are preferred, many other forms of devices might be employed to coöperate with the rotary member 20 and are contemplated.

The segment 11 moves commensurately with the track device but it is desired that the switching device should be positively operated at the initial movement of the track device in one direction and at the end movement of the track device in the opposite direction. To accomplish this purpose the tooth 32 is located adjacent one end of the segment 11.

With the apparatus as illustrated, the first 105 portion of the movement of the member 10, 11 will cause the tooth 32 operatively to engage in the notch 26 and rotate the member 20 with a quick action, the lug 29 passing from its position outside of segment 11 down 110 through slot 13 to the under side of segment 11 so that the segment 11 will then lock the member 20 independently of the means for rotating, viz., tooth 32, by reason of the co-operating locking means, viz., face or stop 34 115 and lug 29. The member 20 will continue to be locked as the member 10, 11 moves to the limit of its travel to the left and through part of its return movement to the right. On the return movement to the right, the tooth 32 120 reengages in the notch 26; the lug 29 passes up through slot 13 as the member 20 rotates counter clockwise; and then the segment 11 again locks member 20 against rotation independently of the tooth 32 by means of the face or stop 33 and lug 29 both now on the outer face of segment 11.

For some purposes the device 24 notched at 26 may be regarded as a device provided with two spaced abutments which are sub- 125

stantially what the sides of the notch 26 form and which coöperate with the tooth 32 to rotate the member 20.

If the switch instrument were always to be located in the same position relatively to the track device and to operate always in the same manner it would not be necessary to render its operating parts reversible. However this is not the case as will be seen by an inspection of Fig. 4. 85 and 86 illustrate the rails of a main line in a block limited by the insulating joints, 109, 110, 111, and 112, while 87 and 88 illustrate the rails of a siding in a block limited by the insulating joints 113, 114, 89 and 90. 79 and 80 are switch points pivoted respectively at 91 and 92. They operate as is well known in the art to give admittance to and from the siding 87 and 86. These switch points are connected by a cross bar 82 which comprises an insulating section. 81. To this cross bar 82 is fixed an offset shaft 83 which is operated by a lever 84 to throw the switch. This lever 84 although diagrammatically shown as directly connected with the rod 82 may be at any suitable distance therefrom and may operate through the medium of links, or in any way. The crank 5 of the switch instrument 1 is pivoted to the operating shaft 83 and therefore is moved commensurately with the bar 82 and the switch points. The switch instrument 1 is illustrated as attached to the tie 78 at the end 76 with its crank 5 on the right hand side thereof. It might be necessary, however, on account of some obstruction, to place the switch instrument at the other end 75 of the tie or possibly on the tie 77 at either the end 73 or the end 74. It is such changes as these in the position of the switch instrument which necessitate corresponding changes in the relative disposition of the operating mechanism in the instrument, as have been heretofore described.

In Fig. 5 is illustrated a possible application of the switching devices embodied in the instrument to a railway signaling system. The rails 87, 88 of the siding are provided with insulating joints 89, 90 respectively which together with the insulating bar 83 prevent short circuiting of the rails by the rails of the switch points. Both sets of rails are supplied with current from the battery 93, through the wires 94, 95 and 107. The magnet 100, connected to the rails by wires 98, 99, is therefore normally energized and maintains its armature 103 normally in contact with stop 108 closing the circuit of signal 106 from battery 104, through wire 102, switching device 40, 50, 49 and 39, wire 101, back to battery 104, thus holding the signal at clear. When the switch points 79 and 80 are thrown the switching device 44, 47, 48, 43 is closed and the rails 85 and 86 are connected through wires 96, and 97, thus shunting out the magnet 100. This breaks the

circuit of signal 106 which goes to danger. This signal circuit is also broken at 39 by the opening of the switching device at that point. This diagram is merely illustrative of one of many uses to which the switch instrument 70 may be applied and it is obvious that many other circuits than those designated might be controlled by the switching devices provided in the instrument.

While the invention is shown in what is now believed to be its best form and with a wide range of adaptability, it is obvious that its features may be variously modified in form and arrangement without departing from the substance of the invention.

What I claim and desire to secure by Letters Patent is:

1. In a switch instrument for track devices, the combination of a rock shaft operable by movement of the track device, a member secured thereto extending radially therefrom and having a curved bearing surface at its outer end, electric switch mechanism coöperating actuating parts upon said switch mechanism and near one end of said surface respectively, and means independent of said actuating connections for locking said electric switch mechanism by said surface when said actuating connections are disengaged.

2. In a switch instrument for track devices, the combination of a rock shaft operable by movement of the track device, a member secured thereto extending radially therefrom and having a curved bearing surface at its outer end, electric switch mechanism coöperating actuating parts upon said switch mechanism and near one end of said surface respectively, locking parts independent of the actuating parts upon said switch mechanism and said surface respectively arranged to lock said switch mechanism in each of its positions, and means for releasing said locking parts at the actuating position of the radially extending member.

3. In a switch instrument for track devices, electric switch mechanism, a swinging segment operable from the track device, an actuating connection between the segment near one end thereof and said switch mechanism, said switch mechanism and segment respectively carrying coöperative locking surfaces independent of the actuating connection and arranged to lock the switch mechanism except when the actuating connection is operative.

4. In a switch instrument for track devices, electric switch mechanism, a swinging segment operable from the track device, a tooth and a notch carried one upon the swinging segment near one end thereof and the other by said switch mechanism, said switch mechanism and swinging segment having locking surfaces independent of the tooth and notch and arranged to lock the

switch mechanism except when the tooth is engaging the notch.

5. A horizontally disposed switch mechanism pivotally mounted, a swinging segment 5 operable from a track device, a tooth and notch carried one by the switch mechanism and the other near one end of the segment, said switch mechanism and segment carrying coöperating locking surfaces engaging each 10 other except when the segment is at a position to bring the tooth and notch in engagement.

6. In a switch instrument for track devices, a case; a rock shaft supported thereby; 15 a switch operating rocking frame carried by the case and provided with an operating face; means on the rock shaft to engage the operating face on the rocking frame to tilt the rocking frame and means for locking said 20 frame in position during a certain range of movement of the rock shaft.

7. In a switch-instrument for track devices, a plurality of switches oppositely arranged; a rocking frame extending adjacent 25 thereto; links operatively connecting each side of the rocking frame with the respective switches; an operating face on the rocking frame; and a rocking member to engage said face and operate the rocking frame.

30 8. In a switch-instrument for track devices, a plurality of switches oppositely arranged; a rocking frame extending transversely thereto; links operatively connecting each side of the rocking frame with the 35 respective switches; a cam on the rocking frame; and a rocking member to engage said cam and operate the rocking frame.

9. In a switch-instrument for track devices, a plurality of switches; a rocking 40 frame extending adjacent thereto and links operatively connecting the rocking frame with the respective switches.

45 10. In a switch-instrument, a reversible switching device, an operating rocking frame extending transversely to said switching device; and a reversible link mechanically connecting said switching device with one side of said rocking frame.

50 11. In a switch-instrument, a plurality of reversible interchangeable switching devices; an operating rocking frame extending transversely to the switching devices; and a plurality of reversible interchangeable links each connecting a switching device with one 55 side of the rocking frame.

12. In a switch-instrument, a plurality of reversible interchangeable switching devices; an operating rocking frame extending transversely to the switching devices; and a 60 plurality of reversible interchangeable insulated links each connecting a switching device with one side of the rocking frame.

65 13. In a switch-instrument, a plurality of reversible interchangeable switching devices; an operating rocking frame extending

transversely to the switching devices; and a plurality of reversible interchangeable links insulated from each other and from the rocking frame and each connecting a switching device with one side of the rocking frame. 70

14. In a switch-instrument, a plurality of reversible interchangeable switching devices; an operating frame extending transversely thereto and comprising two parallel rods one on each side; a tube of insulating 75 material surrounding each rod; reversible, interchangeable links; one end of each link comprising a sleeve embracing said tube; the other end of each link connected to a switching device; interchangeable insulating washers on the tube of insulating material and alternating with the said link sleeves thereon; and interchangeable insulating washers on the ends of said tube of insulating material. 85

15. In a switch-instrument, a plurality of reversible interchangeable switching devices; an operating frame extending transversely thereto and comprising two parallel rods one on each side; a tube of insulating 90 material surrounding each rod; reversible, interchangeable links, one end of each link comprising a sleeve embracing said tube, the other end of each link connected to a switching device; blank sleeves also embracing said tube; interchangeable insulating washers on the tube of insulating material and alternating with the said link sleeves and blank sleeves thereon; and interchangeable insulating washers on the ends of the tubes 100 of insulating material. 95

16. In a switch-instrument, a signal switching device comprising an integral substantially Z-shaped blade and base member of spring metal; the contact end of the blade 105 twisted at an angle of 90° to the blade proper and forming a knife contact; and a coöperating contact member for said knife contact.

17. In a switch-instrument for track devices, signal switching devices; an operating rocking frame for said switching devices; actuating means for said rocking frame operable from either side of the track device and means for locking said frame in position during a certain range of movement of said 115 actuating means.

18. In a switch-instrument for track devices, signal switching devices; an operating rocking frame for said switching devices; reversible actuating means for said rocking 120 frame operable from either side of the track device and means for locking said frame in position during a certain range of movement of said actuating means.

19. In a switch instrument, an operating rocking frame for a switch; a notched device at one end of the frame; a locking lug projecting from the frame at one side of said notched device; a coöperating reciprocating segment adjacent said notched device to en- 125 130

gage said device and said locking lug and lock the rocking frame; and said segment provided with a tooth near one end to engage said notched device and with a slot in the segment simultaneously to release said locking lug.

20. In a switch-instrument, an operating rocking frame for a switch; a notched device at one end of the frame; said frame provided with a slot on each side of said notched device; an interchangeable locking lug fixed to the frame and projecting through one of said slots; a coöperating reversible reciprocating segment adjacent said notched device to engage said device and said locking lug and lock the rocking frame; said segment provided with a tooth near one end to engage the notched device and a slot in each edge of the segment to release the locking lug when the cam is engaged by said tooth and render the segment reversible.

21. In a switch-instrument for track devices, a case; switching devices therein; a

supporting shelf for said switching devices projecting from an interior wall of the case 25 toward the opposite wall and leaving an open space adjacent said opposite wall for operating means for the switching devices.

22. In a switch-instrument for track devices, a case; a transverse rock shaft; switching devices; a supporting shelf for said switching devices projecting above said rock shaft from one wall of the case and supported by brackets, extending from the wall of the case on each side of said rock shaft; an 35 operating means for the switching devices fixed to said rock shaft and free to move in an open space adjacent the wall of the case opposite the supporting shelf.

In testimony whereof, I have signed my 40 name to this specification, in the presence of two subscribing witnesses.

CLARENCE W. COLEMAN.
